ATTORNEY

UNITED STATES PATENT OFFICE

EMIL STRANSKY, OF WARREN, PENNSYLVANIA

RESISTANCE GRID

Application filed March 19, 1930. Serial No. 437,119.

This invention relates to a resistance grid and to the method of making the same, the grid being composed of warp and weft members, with the major portions of the weft members formed of resistance wire, the general object of the invention being to provide reinforcing bars which extend parallel to the weft and act to make the grid rigid in the direction of its weft, such reinforcing bars, when necessary or desired, having their ends extending beyond the grid so as to form supporting means for the grid and electrical connections where the reinforcing bars are electrically connected with the weft wires.

Another object of the invention is to provide the grid with projections of insulating material on its faces for preventing the grid from contacting members on which it is placed or which are placed on the grid, these projections being carried by the reinforcing bars or otherwise attached to the grid.

Another object of the invention is to provide the grid with a protecting coating of refractory material which acts as a support to the warp.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a plan view, partly diagrammatic, of the grid.

Figure 2 is a section on line 2-2 of Figure 1.

Figure 3 is a diagrammatic view of the circuit formed by the weft wires.

Figure 4 is a fragmentary plan view showing the insulators as formed of blocks and showing a supporting tab extending from one edge of the grid.

Figure 5 is a diagrammatic plan view showing the grid provided with a thermo-couple.

Figure 6 is a view of one of the tubular insulators shown in Figures 1 and 2.

Figure 7 is a view of one of the blocks shown in Figure 4.

Figure 8 is a view of the attaching tab shown in Figure 4.

As shown in these views, the grid is composed of the warp members 3 and the weft members 4, the major portions of the weft members being formed of resistance wire and the warp members being composed of asbestos or suitable material covered with asbestos or other heat resisting matter. The grid is provided with a selvedge 5 at each edge.

In carrying out my invention, I place reinforcing bars 6 in the grid, these bars extending parallel to the weft members 4 and they act to make the grid rigid transversely or in the direction of the weft members. They are woven in the grid and if desired, the ends of the bars may project from the edges of the grid, as shown at 6', to form means for attaching the grid to a supporting member, and if the bars are electrically connected to the weft members, as shown at 7 in Figure 3, the projecting ends can serve as means for connecting the bars to a source of electric supply.

Tubular members 8, of non-conducting material, may be placed on the bars to prevent the grid from coming in electrical contact with a member on which it is placed or a member placed on the grid.

One or more of the bars may be formed of different metals, as shown at 6" in Figure 5, to form a thermocouple.

Blocks 9, of non-conducting material, may be suitably connected with the grid and extend beyond the faces thereof so as to prevent the grid contacting the members placed above or below the grid.

Tabs 10 may be connected to the edges of the grid to provide means for supporting the grid from a supporting member and if desired, these tabs can be electrically connected to the resistance wire and to a source of supply.

The grid is coated with refractory material, such as a mixture of silicate basic solution

containing English ball clay and silica, and his coating can be replaced by an enamel coating. The silicate coating will be a considerable support to the warp.

This invention enables resistance grids to be cheaply manufactured and they have considerable strength and can be supported on two or four sides and by using the projections of insulating material, there is no danger of the grid contacting with members placed on each side of it.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A resistance grid comprising woven warp and weft members and the warp members composed of non-inflammable material and the weft members composed of resistance material, and reinforcing bars extended between the warp members and extending parallel with the weft members and projecting at one end beyond the weft members to provide supports for the attachment of conductors thereto.

2. A resistance grid comprising woven warp and weft members and the warp members composed of non-inflammable material and the weft members composed of resistance material, reinforcing bars extended between the warp members and extending parallel with the weft members and projecting at one end beyond the weft members to provide supports for the attachment of conductors thereto, and insulating sleeves arranged on the bars and in spaced relation to prevent the warp and weft members from coming in contact with other objects located adjacent thereto.

In testimony whereof I affix my signature.
EMIL STRANSKY.
